JAMES A. BIERREGAARD, OF FOREST HILLS, NEW YORK, ASSIGNOR TO DOHERTY RESEARCH COMPANY, OF NEW YORK, N. Y., A CORPORATION OF DELAWARE

LIQUID STORAGE RESERVOIR

Application filed April 14, 1931. Serial No. 529,936.

This invention relates to liquid storage reservoirs and more particularly to a novel design of large capacity oil storage reservoirs of the earth embankment type and a floating roof therefor.

In designing and building large capacity oil storage reservoirs heretofore it has not been found practicable to combine the qualities of stability, durability, comparatively inexpensive construction and high efficiency in preventing oil loss by seepage and evaporation. Various types of large capacity reservoirs have been suggested as embodying one or more of these qualities but in each of such suggested reservoirs at least one of the above qualities so essential to efficient oil storage is lacking. Particularly in reservoirs of the earth fill or earth embankment type it has been found impossible heretofore to combine in both the reservoir design and in the roof design a comparatively inexpensive construction, and stability, with high efficiency in the prevention of oil losses due to leakage and evaporation.

One object of the present invention is to provide a large capacity liquid storage reservoir of the earth embankment type which is stable, durable, comparatively inexpensive to build and is highly efficient in preventing losses by leakage and evaporation.

Another object of the present invention is to provide a floating roof for such a large capacity liquid storage reservoir of the earth embankment type which will be of simple and inexpensive construction and of high efficiency in preventing evaporation losses under all weather conditions.

Other objects and advantages of the invention will be apparent from the following detailed description, taken with the accompanying drawings, in which:

Fig. 1 is a partly diagrammatic top plan view of an oil storage reservoir and roof embodying the preferred design of the present invention.

Fig. 2 is an enlarged plan view of one portion of the reservoir roof shown in Fig. 1, parts being broken away to show the construction of underlying parts.

Fig. 3 is a view in vertical cross-section

of a part of the reservoir according to the present invention, showing the relation of the floating roof to the walls and floor of the reservoir.

Figs. 4, 5, 6, and 7 show various forms of joints which may be used to advantage in the construction of the reservoir roof.

Referring to the drawings, 10 indicates the earthen wall of the earth embankment type reservoir according to the present invention. 60 This wall may be circular or oval in shape and may be of any suitable dimensions so as to provide a reservoir of the desired capacity. The wall is banked on both sides to such a degree that it is stable under full 65 capacity pressure. The inside surface of the wall embankment 10 is constructed in a series of steps 12 extending inwardly from the top to the floor 14 of the reservoir, and each step is retained by a vertical ring 16 of corrugated metal or concrete which extends a short distance above the surface of each step. The top surface of each step 12 and of the reservoir floor 14 is treated with asphaltum 70 so as to make the surfaces impervious to water. In this way the tendency of the wall embankment or the floor of the reservoir to absorb the water, such absorption tending toward a subsequent instability of the wall embankment, is obviated, and by reason of 75 the retaining rings 16 a body of water 18 is constantly maintained on each of the steps 12 of the embankment. Similarly, a body of water 19 is constantly maintained on the floor 14 of the reservoir by reason of a water outlet pipe 20 having an outlet opening 80 which is slightly above the floor level of the reservoir. Liquid for the water bodies 18 and 19 is introduced through an inlet pipe 21 located above the top step of the reservoir 85 wall which maintains a body of water. The reservoir is also provided with an oil inlet and outlet pipe 22.

Referring now more particularly to the roof 23, 24 indicates the curved pans of the peripheral portion 25 of the roof which are joined together at 26 and 28 in a manner which will hereinafter be more fully described. The pans 24 are of inverted semi-cylindrical cross section constructed of flexi- 95 100

ble sheet metal and are joined together both endwise and sidewise to form a series of connected annular rings 27, the rings being concentrically arranged and overlying the steps 5 12 of the inside surface of the wall embankment.

The central portion of the roof 29 is composed of rectilinear rows of straight pans 30 of inverted semi-cylindrical cross section 10 constructed of flexible metal and joined together at 32 and 34. The joints 32 and 34 are formed in a manner which will be hereinafter more fully explained. The central portion of the roof 29 overlies the floor 14 15 of the reservoir.

The central series of pans 30 are joined to the peripheral series of pans 24 at 36 in any suitable manner such as by welding or bolting. The outer series of pans 24 of the 20 peripheral portion of the roof are joined to the walls of the reservoir by means of a metal ring strap 38. This strap 38 is welded or bolted or fastened in any other suitable way to a ring 40 which retains one of 25 the upper steps of the wall embankment so that the joint thus made will be practically air-tight and liquid-tight.

Above the peripheral portion 25 of the roof is placed a series of annular pontoon members 42 constructed of metal tubing and attached to the annular rows of pans 24 at the joints 28 between the various rows by means of guys 44. Similarly above the central portion 29 of the roof is a series of 30 rectilinear pontoon members 46 constructed of metal tubing and attached to the rectilinear rows of pans 30 at the joints 34 between the various rectilinear rows by means of guys 48. The purpose of these pontoon members will 35 be more fully hereinafter discussed. Above the roof and to one side of the reservoir is a water inlet pipe 50 for providing a water seal for the reservoir.

Figs. 4 and 6 show forms of joints which 40 may be used at 26 and 32, Fig. 4 showing a bolted joint having a gasket 52 and bolting bars 54, and Fig. 6 showing a pressed joint. Figs. 5 and 7, show forms of joints which 45 may be used at 28 and 34, Fig. 5 showing a bolted joint having a gasket 56 and bolting bars 58, and Fig. 7 showing a rolled joint. While any suitable type of joint may be used in the construction of the roof of the reservoir according to the present invention, the 50 types above described are preferable in that they can be made practically air-tight and liquid-tight, and their simple design facilitates quick and easy assembly of the roof.

When the reservoir is full, the roof will 60 take the position shown at 60, since by reason of the air-tight and liquid-tight connections between the various sections of the roof it will float on the surface of the oil in the reservoir. By allowing the water to flow 65 from the water inlet 50 onto the roof a water

70 seal is formed and maintained above the roof, the roof then acting as a flexible membrane between the oil and the water. A slight flow of water is constantly maintained from the inlet pipe 21 on to the steps 12 and progressively downwardly from step to step until it finally reaches the floor of the reservoir. The 75 water level on the floor 14 may be maintained constant by allowing the superfluous water to escape over the weir at the top of the pipe 20. Thus a constant level of water may be maintained on the roof, the steps, and the floor of the reservoir, which bodies of water 80 act as a complete water seal for the body of oil in the reservoir.

When the oil is withdrawn from the reservoir through the pipe 22 the oil level will drop and the roof will drop accordingly to a position shown at 62. As the roof lowers, the flexibility of the metallic pan and pan joint construction allows the pan rows to 85 diametrically expand and flex so that the peripheral joints 28 between the outer annular rows of pans will rest upon each successively lower step 12, the joints between pan rows 90 being water-sealed by the body of water which is maintained at each step, and by that portion of the water above the roof as shown at 95 64 which normally remains between the series of pans as the roof lowers, thus giving an increasingly tighter water seal to the oil within the reservoir. The pontoon members 42 will lower with the surface of the water constituting the water seal above the roof until 100 they rest upon and between the outer rows 105 of pans 24.

When the oil is substantially all withdrawn 110 from the reservoir, the roof will lower to the position shown at 66 so that the central portion of the roof will rest upon the floor of the reservoir. When desired the reservoir may be again filled by flowing the oil into the reservoir through the pipe 22, and the roof will be raised accordingly.

Inasmuch as the roof acts only as a flexible 115 membrane between the oil in the reservoir and the water seal above the roof, it is subject to any differential in pressure between the oil and the water at any point on the surface of the oil. Accordingly the roof must be stabilized in some way as by means of the pontoon member 42 and 46. If the water above the roof is displaced by any of a number of causes such as the application of a local load 120 or the action of the wind on the free water surface, the tendency in a roof design not provided with pontoon members is for this unequal distribution to become worse. However, according to the roof design of the present invention any tendency for the roof membrane to lower pulls down the pontoon members which are only normally partially submerged and gives additional buoyancy to that portion of the roof, thus tending to pull the roof back to its normal position. Likewise 125

any tendency of the roof membrane to lift is resisted by the overlying water when the buoyancy of the pontoon members is reduced. The roof is therefore constantly in a state 5 of stable equilibrium.

It may be seen from the above detailed description that the reservoir and roof design of the present invention is of high durability, is of great stability, is of comparative-
10 ly inexpensive and simple construction and is of high efficiency in preventing oil loss by seepage and evaporation. The reservoir and roof have particularly high efficiency in preventing oil loss by evaporation or leakage, 15 since the body of oil is completely enclosed by water seals.

An additional advantage of the roof design is that the units of the roof may be shop fabricated, shipped nested, and erected in the field.
20 The bolted joints between the pan units are also of particular advantage here in that they facilitate erection of the roof and allow replacement of pan units without emptying the reservoir. Easy replacement may be
25 effected by removing the water seal and blowing the air into the pans in the rows adjacent the row in which the pan is to be replaced, thus raising that portion of the roof sufficient-
ly to allow the replacement.

30 What is claimed as new is:

1. An oil storage reservoir having upward-
ly diverging inner side walls formed as a
series of steps and means for retaining indi-
35 vidual steps and for maintaining bodies of
liquid on each step.

2. An oil storage reservoir having a floor
and upwardly diverging side walls with a
stepped inner surface, the surface of said
40 floor and said steps being treated to be im-
pervious to water, means for retaining indi-
vidual steps and for maintaining a body of
water on each step and means for maintain-
ing a body of water on said floor.

3. An oil storage reservoir having side
45 walls with a sloping inner surface and a flexi-
ble roof of a cross-sectional area sufficient to
cover the surface of the oil when the reservoir
is full and to extend to the upper periphery
of the reservoir wall to which it is fastened,
50 said roof consisting of a plurality of flexible
metal segments connected end to end and side
by side in rows by air-tight and liquid-tight
joints so as to float on the surface of the oil
within the reservoir and by its flexibility to
55 conform to the shape of the wall and to rest
thereon as the level of the oil in the reservoir
is lowered.

4. An oil storage reservoir having inner
60 side walls formed as a series of steps and a
roof of sufficient cross-sectional area to cover
the surface of the oil when the reservoir is
full and to extend to the upper periphery of
the reservoir wall to which it is fastened, said
65 roof consisting of a plurality of inverted
flexible metal pans of semi-cylindrical cross

section connected end to end and side by side
in rows by air-tight and liquid-tight joints so
as to float upon the surface of the oil and the
70 peripheral portion of said roof consisting of
pan rows that overlie and conform to the
shape of the steps of the side walls so that the
joints between said pan rows will rest upon
successively lower steps of the wall as the
75 level of the oil in the reservoir is lowered.

5. An oil storage reservoir roof consisting
of a plurality of inverted flexible metal pans
of semi-cylindrical cross section connected
80 end to end and side by side in rows by air-
tight and liquid-tight joints, said roof being
adapted to float upon the surface of the
oil within the reservoir and to conform in
contour with upwardly diverging reservoir
85 walls.

6. An oil storage reservoir roof comprising
90 a plurality of flexible metal segments of
two different patterns the segments of one
pattern having curved edges to conform to the
shape of the reservoir wall and the segments
of the other pattern having straight edges,
95 said segments being connected end to end
and side by side in rows by air-tight and
liquid-tight joints to form a peripheral roof
section of annular concentric segment rows
100 and a central roof section of rectilinear par-
allel segment rows.

7. An oil storage reservoir roof having a
105 peripheral portion and a central portion, the
said peripheral portion consisting of a plu-
rality of flexible metal pans of inverted semi-
cylindrical cross section connected end to end
and side by side in rows by air-tight and liq-
uid-tight joints shaped to conform to the con-
110 tour of the reservoir and to form an annular
concentric series of pan rings, and the said
central portion consisting of a plurality of
flexible metal pans of inverted semi-cylin-
115 drical cross section connected end to end and
side by side in rows by air-tight and liquid-
tight joints to form a parallel rectilinear se-
ries of pan rows, the said peripheral portion
120 having air-tight and liquid-tight connections
with the said central portion.

8. An oil storage reservoir comprising
125 sloping side-walls and a roof, said roof con-
sisting of a peripheral portion and a central
portion of flexible metal pans of inverted
semi-cylindrical cross section, connected end
to end and side by side in rows by air-tight
130 and liquid-tight joints, the said peripheral
portion forming an annular concentric se-
ries of pan rings and the said central portion
forming a parallel rectilinear series of pan
rows, the said peripheral portion having air-
tight and liquid-tight connections with the
wall of the reservoir and with the said cen-
tral portion so that the said roof will float
upon the surface of a body of oil within the
reservoir, and a water seal above said roof.

9. An oil storage reservoir having a roof,
135 a floor and side walls with a stepped inner

- surface, said roof consisting of a peripheral portion and a central portion of a plurality of flexible metal pans of inverted semi-cylindrical cross-section connected end to end and side by side in rows by air-tight and liquid-tight joints so as to form a series of pan rows which float upon the surface of a body of oil within the reservoir, the pan rows of said peripheral portion overlying and conforming to the shape of the steps of the side walls and having a width substantially the same as the width of said steps so that the joints between said pan rows will rest upon successively lower steps of the wall as the level of the oil in the reservoir is lowered and the pan rows of the said central portion overlying the floor of the reservoir so as to rest thereon when the oil supply within the reservoir is sufficiently depleted. 80
10. An oil storage reservoir, having sloping side walls and a roof, said roof consisting of a plurality of inverted flexible metal pans of semi-cylindrical cross section connected end to end and side by side in rows and to the upper periphery of the said side walls by air-tight and liquid-tight joints, a water seal upon said roof and a series of pontoon members attached to and above said roof. 85
11. An oil storage reservoir having side walls and a roof, said roof consisting of a peripheral series of concentric rows of flexible metal pans of inverted semi-cylindrical cross section connected end to end and side by side by air-tight and liquid-tight joints and a central series of rectilinear rows of flexible metal pans of inverted semi-cylindrical cross section, connected end to end and side by side by air-tight and liquid-tight joints, a water seal above said roof, an annular concentric series of pontoon members attached to and above the peripheral portion of said roof and a parallel rectilinear series of pontoon members attached to and above the central portion of said roof. 90
12. An oil storage reservoir having a floor, side walls with a stepped inner surface, a roof consisting of a plurality of flexible metal segments connected end to end and side by side in rows by air-tight and liquid-tight joints and connected to the upper periphery of the wall of said reservoir, means for retaining said steps and for maintaining a water seal thereon, means for maintaining a water seal on said floor and means for maintaining a water seal above said roof. 95
13. An oil storage reservoir roof having a plurality of flexible segments connected end to end and side by side in rows by air-tight and liquid-tight joints, said roof being adapted to float upon the surface of the oil within the reservoir and to conform in contour with the reservoir walls, a water seal above said roof and a series of pontoon members attached to and above said roof for keeping said roof in equilibrium with the water seal thereabove. 100
14. In a volatile liquid storage reservoir a flexible floating roof covering stored liquid within said reservoir, means for maintaining a water seal over said roof and a series of pontoon members attached to and above said roof for maintaining said roof in equilibrium with said water seal. 105
